UNITED STATES PATENT OFFICE.

JOHN B. WEST, OF SYRACUSE, NEW YORK.

DUPLICATING-MACHINE.

1,149,607.

Specification of Letters Patent. Patented Aug. 10, 1915.

Application filed August 16, 1909. Serial No. 513,000.

To all whom it may concern:

Be it known that I, JOHN B. WEST, of Syracuse, in the county of Onondaga and State of New York, have invented a certain 5 new and useful Duplicating-Machine, of which the following is a specification.

My invention has for its object the production of a particularly simple and efficient printing machine for duplicating letters and 10 other matter; and it consists in the combinations and constructions hereinafter set forth and claimed.

In describing this invention, reference is had to the accompanying drawings in which 15 like characters designate corresponding parts in all the views.

Figure 1 is a plan, partly broken away, of my duplicating machine. Figs. 2 and 3 are, respectively, front and side elevations thereof, parts being broken away in Fig. 3. Fig. 4 is a transverse sectional view, partly broken away. Fig. 5 is a side elevation similar to Fig. 3, the position of the movable frame and parts carried thereby, when the frame 25 is swung on its hinge, being shown in dotted lines, and the receptacle for the printed sheets being shown in section. Fig. 6 is a detached view of means for raising the paper. Fig. 7 is a section on line A—A, Fig. 30 1. Fig. 8 is a detail view, partly broken away, and partly in section, of one of the guide rollers for the ribbon mechanism. Fig. 9 is a detail view illustrating part of the shifting-means for the impression roller. Fig. 10 is a section through a portion of the 35 track for the impression roller carriage. Fig. 11 is an isometric view of a portion of the chase and the guide for the addressing plate, and contiguous parts.

This duplicating machine comprises, generally, a type bed, a frame movable relatively thereto, a ribbon and ribbon mechanism carried by the frame and movable therewith, the ribbon extending across the 45 type bed, and an impression element movable on the frame over the type bed and the portion of the ribbon interposed between the impression element and the type bed, the frame being movable relatively to the type bed for carrying the ribbon and ribbon mechanism therewith and exposing the type bed.

1 is a type bed, and 2 is a rectangular frame inclosing the type bed and movable

relatively thereto, the type bed and the frame being mounted on a base 3, and the frame being pivoted or hinged at 4 to said base.

The base is formed with V-shaped tenons 5, Figs. 2 and 4, on its upper face which enter similarly shaped grooves in the lower edges of the side plates or elements of the frame 2. The frame is normally prevented from movement on its hinge 4 by means of a locking lever or latch 6, Fig. 2, pivoted to the base and movable laterally on its pivot into and out of an inclined slot 7 formed in a downwardly-extending lug 8 on the frame 2 near the front end thereof.

The base is mounted upon a suitable receptacle 9, Fig. 5, which receives the printed sheets of paper and supports a suitable inclined holder or shelf 10 for the blank sheets. Said holder or shelf is here shown as mounted on an arm 11 pivoted at 12 to a bracket 13 fixed to the rear end of the receptacle 9. The holder or shelf 10 is provided with a back 14 which is arranged at an inclined angle thereto in order to hold the blank sheets of paper 15 so that the topmost sheet 70 always projects farther toward the operator than the under sheets, and hence owing to the incline of the shelf and the back, the sheets can easily be removed one by one. Said receptacle 9 is also provided with a drawer 16 and with a paper deflector or shield 17 pivoted thereto at 18 and arranged to guide the paper into the drawer 16. The drawer is provided with a deflector 19 at its rear end for directing the printed sheets of 75 paper into the drawer after they leave the deflector 17. Paper guides 20 are also provided near the deflector 17 for directing the paper leaving the type bed to the deflector 17. Said guides 20 are mounted on a shaft 95 21 held at its ends in the sides of the frame 2, the upper end of the deflector 17 curving over the lower ends of the guides 20, so that when the advance edge of the paper leaves the guides 20, it strikes the deflector 17. The 100 deflector 17 is adjustable about its pivot, and the shaft 21 is adjustable about its axis, and both of these parts are held in their adjusted positions by any desirable means.

The type bed is provided with any suitable means as a chase 22, Fig. 4, for holding the type 23.

24 are ribbon spools carried by outwardly-

extending lugs 25 on opposite side elements of the rectangular frame 2, and 26 is a ribbon unwinding from one of said spools and feeding across the type bed or chase and 5 winding on the other spool 24, said spools 24 being located below the printing plane of the type and the ribbon 26 being guided in its movement across the type bed by two pairs of rollers 27 and 28, one of the rollers 10 27 and one of the rollers 28 being located on each side of the type bed 1 or chase 22, and the rollers 28 being located within the sides of the frame and near the printing plane of the type and being removable for facilitating 15 the insertion of a new ribbon. As seen in Fig. 8, each roller 28 is carried by bearings 29, 30 supported by the frame 2. The bearing 30 comprises a flat spring fixed at one end to the contiguous part of the frame, 20 the other end thereof being free and provided with an opening for receiving the axle 31 of said roller 28. Either of the rollers 28 can be easily withdrawn by moving the same axially against the action of the spring 25 30 engaged therewith until the axle at the other end of such roller is out of the bearing 29.

The ribbon spools 24 are actuated by means of a driving shaft 32, Fig. 2, extending crosswise of the front end of the machine and having beveled gears 33 at its opposite ends which mesh respectively with companion gears 34 provided on the spools 24, the shaft 32 being shiftable by hand axially to carry one of the gears 33 out of mesh with its companion 34 and the other of said gears 33 into mesh with its companion 34 and thus reverse the feed of the ribbon. The shaft 32 is also provided with a ratchet 35 wheel 35 which is actuated by a pawl 36, Fig. 3, carried by a rock arm 37 loosely mounted on the shaft 32, said arm being actuated by the carriage for the impression roller in any suitable manner. A spring 370 40 is connected to the rock arm 37 for returning said arm to its normal position.

38 is a carriage movable along tracks provided on the frame 2, and supporting an impression element or roller 39 movable over the type bed and the portion of the ribbon interposed between the type bed and said roller for effecting the printing upon the paper lying on the ribbon beneath the impression roller 39. The tracks for the carriage 38 are usually rails 40, Figs. 1, 4 and 10, arranged in grooves 41 formed in the upper faces of the side elements of the frame 2, and overhanging rails 42, Fig. 4, the rails 40 being secured at their ends to the frame 50 and having their intermediate portions pressed upwardly against the peripheries of disks 43 at the ends of the roller 39, by springs 44 arranged in the grooves 41, in order to effect rotation of the roller 39 during the movement of the carriage. Said car-

riage is held on the rails 40 by means of underrunning rollers 45 associated with said carriage 38 and engaging the under faces of the overhanging rails 42. The carriage is provided with a handle 46 by which it can be reciprocated for carrying the impression roller 39 over the face of the type bed. This impression roller 39 is provided at each end with a spindle or axle 47 journaled in an eccentric bearing 48 which is journaled in adjustable bearing blocks 49 supported by the carriage, and means is provided to effect the turning of the eccentric bearings 48 in their bearing blocks 49 for raising the impression roller when the carriage 38 has reached the limit of its initial stroke after effecting the printing, and for lowering the impression roller toward the printing plane as said carriage approaches its starting position. The raising and lowering of the impression roller 39 is effected by rocking shifting arms 50 which are mounted on the eccentric bearings 48 of the axle 47 and cooperate with shoulders provided on the frame 2. The carriage 38, during its reciprocating motion, and as it approaches its initial position during its return stroke, actuates the arm 37 mounted on the shaft 32 and effects a step by step feeding of the ribbon 26, the carriage being provided with a shoulder 51 for engaging said arm 37, this shoulder 51 being here shown as an extension of the axle of one of the underrunning rollers 45.

52 is a paper guide or gage supported by the frame near one side thereof, Figs. 1 and 4, and extending crosswise of the ribbon, said guide or gage being held in position by fastening members, as screws 53, passing through slots 54, the slots permitting adjustment of the guide.

My duplicating machine is provided with means for raising the sheet of paper 55 off the ribbon after the sheet has been printed and holding said paper in the path of suitable means provided on the carriage so that the paper will be removed from the ribbon during the return stroke of the carriage 38 and carried against the deflector 17 and directed against the deflector 19 into the 115 drawer 16 of the receptacle 9.

As best seen in Figs. 1, 6 and 7, the means for raising the paper comprises rock arms or members 56 mounted on the rock shaft 57 journaled in the frame, a rock shaft 58 journaled in the frame and provided with an eccentric portion 59 and also with a rock arm 60 which is pivoted to a link connected by a pin-and-slot to a rock arm 61 mounted on the shaft 57. The fingers or rock arms 56 normally lap over the rear edge of the ribbon and are arranged beneath the paper 55; and the carriage 38 when approaching the limit of its initial stroke operates or lifts these arms 56 into the position indi- 130

cated in dotted lines, Figs. 6 and 7 to raise the edge of the paper into the path of engaging parts 62 on the carriage 38, the engaging parts 62 being normally arranged above the plane of the sheet of paper on the ribbon, as seen in Fig. 7, so that the lower portion or hooks or fingers of the parts 62 normally pass over the sheet. As here illustrated, the fingers 56 are actuated by one of the arms 50 which moves into contact with a yielding member 63 fixed to one of the side elements of the frame and connected to the eccentric portion 59 of the rock shaft 58, the yielding member 63 having two surfaces arranged at an angle to each other, one surface 64 serving as a shoulder for engaging the corresponding shifting arm 50 and limiting the movement of the free end thereof with the carriage so that the impression roller is shifted upwardly, and the other surface 65 being engaged by the end of said shifting arm 50 after this arm has been shifted by the shoulder 64, so that further movement of the carriage 38 toward the extreme end of its initial stroke tends to depress the member 63 and thereby actuate the rock shaft 58, the shaft 57 and rock arms 56. During the return stroke of the carriage 38 the paper engaging parts 62 thereon engage the paper and push the same off the ribbon, and the impression roller depresses the rock arms 56 and parts connected thereto to their normal positions. A yielding member 63 which is unconnected to the rock shaft 57, is provided on the frame for coöperating with the other of the shifting arms 50. As the carriage 38 approaches its initial position on its return stroke the shifting arms 50 engages fixed shoulders 66 on the frame and are thereby rocked to effect the lowering of the impression roller to its normal position. The arms 56 are held in their normal position by suitable means as a spring 67 fixed at one end 45 to the frame and engaged with the flattened portion 68 of a disk 69 on the rock shaft 57.

70 is a guide for inserting a printing or addressing plate 71 under the ribbon and into the channel 72 in the chase 22, said guide being detachably and adjustably mounted on the frame bar or element 73 and having a spring clamp 74 which engages the bar 73 and holds the guide in position on the frame bar 73. The inner end of this guide 70 extends under the ribbon and facilitates the insertion of the addressing plate into the chase. Means is provided for raising the ribbon during the insertion of the addressing plate thereunder, this means being here shown as levers 75 pivoted intermediate of their ends at 76 to opposite sides of the guide 70, one arm of each lever extending under the ribbon and the other arm of one lever engaging a suitable finger engaging piece 77 by means of which said

lever may be depressed in order to raise the other end thereof and thereby elevate the ribbon. The ends of the levers 75 which engage the ribbon are connected by a cross piece 78.

70 My printing machine is particularly advantageous in that the chase can be placed in position and removed by unclamping the lever 6 and raising the frame, ribbon and impression roller into the position shown in Fig. 5, and further in that the addressing plate can be readily changed and inserted under the ribbon and the printed sheets easily and automatically removed.

What I claim is:—

1. In a duplicating machine, a type bed, a frame movable relatively to the type bed, an inking ribbon carried by the frame and extending across the type bed, and an impression element movable relatively to the frame over the portion of the ribbon interposed between the type bed and said element, the frame being movable for carrying the ribbon therewith and exposing the type bed, substantially as and for the purpose described. 80

2. In a duplicating machine, a type bed, a hinged frame, an inking ribbon carried by the frame and extending across the type bed, and an impression element movable over the portion of the ribbon interposed between the type bed and said element, the frame being movable on its hinge for carrying the ribbon therewith and exposing the type bed, substantially as and for the purpose specified. 95

3. In a duplicating machine, a type bed, a frame movable relatively to the type bed, an inking ribbon carried by the frame and extending across the type bed, and an impression element carried by and movable relatively to the frame over the portion of the ribbon interposed between the type bed and said element, the frame being movable for carrying the ribbon therewith and exposing the type bed, substantially as and for the purpose set forth. 100

4. In a duplicating machine, a type bed, a hinged frame, an inking ribbon carried by the frame and extending across the type bed, and an impression element movable on the frame over the portion of the ribbon interposed between the type bed and said element, the frame being movable on its hinge for carrying the ribbon therewith and exposing the type bed, substantially as and for the purpose described. 115

5. In a duplicating machine, a base, a type bed mounted on the base, a frame supported on the base and movable relatively thereto, an inking ribbon carried by the frame and extending across the type bed, and an impression element movable on the frame over the portion of the ribbon interposed between the type bed and said element, the frame being movable relatively to 125

70

the base for carrying the ribbon therewith and exposing the type bed, substantially as and for the purpose specified.

6. In a duplicating machine, a base, a type bed mounted on the base, a frame hinged to the base, an inking ribbon carried by the frame and extending across the type bed, and an impression element movable along the frame over the portion of the ribbon interposed between the type bed and said element, the frame being movable on its hinge for carrying the ribbon therewith and exposing the type bed, substantially as and for the purpose set forth.
- 15 7. In a duplicating machine, a type bed, a frame movable relatively to the type bed, ribbon spools carried by the frame on opposite sides of the type bed, a ribbon extending from one spool to the other across the type bed, and an impression element movable along the frame over the portion of the ribbon interposed between the type bed and said element, the frame being movable relatively to the type bed for carrying the inking ribbon therewith and exposing the type bed, substantially as and for the purpose described.
- 30 8. In a duplicating machine, a type bed, a frame movable relatively thereto, ribbon spools on opposite sides of the frame, a ribbon extending from one spool to the other across the type bed, a reciprocating carriage, an impression element supported by the carriage, and movable over the portion of the ribbon interposed between the type bed and said element, and means for actuating one of the spools to feed the ribbon, including a movable part arranged in position to be moved by the carriage as the carriage approaches the limit of its movement in one direction, and power-transmitting mechanism between said part and one of the spools, said ribbon feeding mechanism being movable with said frame, substantially as and for the purpose specified.
- 45 9. In a duplicating machine, a type bed, a frame movable relatively to the type bed, ribbon spools carried by the frame and located on opposite sides thereof, the ribbon spools having gears associated therewith, a ribbon extending from one spool to the other across the type bed, a reciprocally movable carriage movable along the frame, an impression element supported by the carriage and movable over the portion of the ribbon interposed between the type bed and said element, and means for actuating the spools for feeding the ribbon including a shaft supported by the frame and extending from one side thereof to the other, the shaft being provided with gears for meshing respectively with the gears associated with the ribbon spools and also with a ratchet wheel, and said shaft being shiftable axially for carrying one of the gears thereon out of

mesh with its companion gear and the other gear thereon into mesh with its companion gear and a pawl operable by the carriage as it approaches the limit of its movement in one direction, the pawl co-operating with the ratchet wheel, substantially as and for purpose specified.

10. In a ribbon press, a reciprocating platen carrier, means carried by the platen carrier for delivering the paper, and mechanism operated by the carrier during the reciprocations thereof for holding the paper in position to be caught by said means, substantially as and for the purpose specified.

11. In a duplicating machine, a type bed, a reciprocally movable impression element movable over the type bed for effecting the printing of the paper interposed between the type bed and the impression element, means movable with the impression element for engaging and removing the paper during the return stroke of said element, the paper being normally out of position to be engaged by said means, and means for raising the paper into position to be engaged by the former means, substantially as and for the purpose specified.

12. In a duplicating machine, a type bed, a reciprocally movable impression element movable over the type bed for effecting the printing on the paper interposed between the type bed and the impression element, means movable with the impression element for engaging and removing the paper during the return stroke of said element, the paper being normally out of position to be engaged by said means, and means for raising the paper into position to be engaged by the former means, the latter means being operated by the impression element during its reciprocating movement, substantially as and for the purpose set forth.

13. In a duplicating machine, a type bed, a reciprocally movable impression element movable over the type bed for effecting the printing on the paper interposed between the type bed and the impression element, means movable with the impression element for engaging and removing the paper during the return stroke of said element, the paper being normally out of position to be engaged by said means, and means for raising the paper into position to be engaged by the former means, the latter means being operated by the impression element as the same approaches the end of its initial stroke and being moved to its normal position during the return stroke of said element, substantially as and for the purpose described.

14. In a duplicating machine, a type bed, a frame, a reciprocally movable impression element movable on the frame over the type bed for effecting the printing on the paper interposed between the type bed and the impression element, means movable with the

impression element for engaging and removing the paper during the return stroke of said element, the paper being normally out of position to be engaged by said means, and means for raising the paper into position to be engaged by the former means, the latter means including a rock shaft supported by the frame and having a rock arm adapted to underlie the paper, the rock arm being movable about its axis by the impression element as said element approaches the end of its initial stroke, substantially as and for the purpose specified.

15. In a duplicating machine, a type bed, a frame, a reciprocally movable impression element movable on the frame over the type bed for effecting the printing on the paper interposed between the type bed and the impression element, means movable with the impression element for engaging and removing the paper during the return stroke of said element, the paper being normally out of position to be engaged by said means, and means for raising the paper into position to be engaged by the former means during the return stroke of the impression element, the latter means including a rock arm adapted to underlie the paper, and a rock shaft connected to the rock arm and having an eccentric portion, and a part movable by the impression element and movable into and out of engagement with said eccentric portion, substantially as and for the purpose set forth.

35. 16. In a duplicating machine, a type bed, a frame, a reciprocally movable impression element movable on the frame over the type bed for effecting the printing on the paper interposed between the type bed and the impression element, the impression element having a projecting arm associated therewith, means movable with the impression element for engaging and removing the paper during the return stroke of said element, the paper being normally out of position to be engaged by said means, and means for raising the paper into position to be engaged by the former means, the latter means comprising a movable member for engaging the paper, a movable member arranged in position to be engaged by the arm associated with the impression element, and power-transmitting parts between said members, substantially as and for the purpose described.

55. 17. In a duplicating machine, a type bed, a frame, a reciprocally movable impression element movable on the frame over the type bed for effecting the printing on the paper interposed between the type bed and the impression element, the impression element having a projecting arm associated therewith, means movable with the impression element for engaging and removing the paper during the return stroke of said element,

the paper being normally out of position to be engaged by said means, and means for raising the paper into position to be engaged by the former means, the latter means including a rock arm adapted to underlie the paper, a rock shaft connected to the rock arm and having an eccentric portion and a movable member carried by the frame and co-operating with the eccentric portion of the rock arm, the movable member being arranged in the path of the arm associated with the impression element in order to be moved by said arm to actuate the rock shaft, substantially as and for the purpose specified.

80. 18. In a duplicating machine, a type bed, a frame, a carriage movable on the frame, an impression element supported by the carriage and movable therewith over the type bed for effecting the printing on the paper interposed between the type bed and the impression element, the impression element being shiftable relatively to the carriage toward and from the printing plane and being provided with a shifting arm, means supported by the carriage for engaging and removing the paper during the return stroke of the carriage, the paper being normally out of position to be engaged by said means, and means for raising the paper into position to be engaged by the former means, the latter means comprising a movable member for engaging the paper, a movable member arranged in position to be engaged by said shifting arm, and power-transmitting parts between said members, substantially as and for the purpose set forth.

95. 19. In a duplicating machine, a type bed, a frame, a carriage movable on the frame, an impression element supported by the carriage and movable therewith over the type bed for effecting the printing on the paper interposed between the type bed and the impression element, the impression element being shiftable relatively to the carriage toward and from the printing plane and being provided with a shifting arm, means supported by the carriage for engaging and removing the paper during the return stroke of the carriage, the paper being normally out of position to be engaged by said means, and means for raising the paper into position to be engaged by the former means, the latter means comprising a movable member for engaging the paper, a movable member arranged in position to be engaged by said shifting arm, and power-transmitting parts between said members, substantially as and for the purpose set forth.

105. 110. 115. 120. 125. 130. 19. In a duplicating machine, a type bed, a frame, a carriage movable on the frame, an impression element supported by the carriage and movable therewith over the type bed for effecting the printing on the paper interposed between the type bed and the impression element, the impression element having a projecting arm associated therewith, means movable with the impression element for engaging and removing the paper during the return stroke of said element, the paper being normally out of position to be engaged by said means, and means for raising the paper into position to be engaged by the former means, the latter means comprising a movable member for engaging the paper, a movable member arranged in position to be engaged by said shifting arm, the last-mentioned member having surfaces arranged at an angle to each other, one surface engaging the shifting arm and causing the same to shift the impression element in one direction during the movement of the carriage and the other surface being engaged by the end of the shifting arm after the same has been moved by the first-mentioned surface for effecting the op-

eration of said movable member, and power-transmitting parts between said members, substantially as and for the purpose described.

- 5 20. In a duplicating machine, a type bed, a frame, a reciprocally movable carriage along the frame, an impression element supported by the carriage and movable therewith over the type bed for effecting the 10 printing on the paper interposed between the type bed and the impression element, the impression element being also shiftable relatively to the carriage away from the printing plane as the carriage approaches 15 the limit of its initial stroke and toward the printing plane as the carriage approaches its starting position, said impression element having a rocking shifting arm associated therewith, means movable with the 20 carriage for engaging and removing the printed paper during the return stroke of the carriage, the paper being normally out of position to be engaged by said means, and means for raising the paper into position 25 to be engaged by the former means, the latter means including a rock arm adapted to be inserted under the paper, a rock shaft journaled in the frame and connected to the rock arm and having an eccentric portion and a yielding member carried by the 30 frame and coöperating with the eccentric portion of the rock arm, the yielding member having surfaces arranged at an angle to each other, one surface being arranged in 35 the path of the shifting arm to be engaged thereby and thereby effect the rocking of said arm and the other surface being engaged by the end of the shifting arm after the shifting arm has been rocked and there- 40 by operating the yielding member for actuating the eccentric portion of the rock shaft and operating the rock arm engaging the paper, substantially as and for the purpose specified.
- 45 21. In a duplicating machine, a type bed, a frame element extending crosswise of the type bed, a ribbon extending crosswise of the type bed, means for feeding the ribbon, and a guide carried by the frame element 50 for guiding a printing plate under the longitudinal edge of the ribbon in a direction at an angle to the direction of movement of the ribbon, substantially as and for the purpose set forth.
- 55 22. In a duplicating machine, a type bed, a frame element extending along the type bed, a ribbon extending crosswise of the type bed, and a guide carried by the frame element for guiding a printing plate under the 60 ribbon, said guide being adjustable along the frame element, substantially as and for the purpose described.
- 65 23. In a duplicating machine, a type bed, a frame element extending along the type bed, a ribbon extending crosswise of the type

bed, a guide carried by the frame element for guiding a printing plate under the ribbon, and means for raising the ribbon during the insertion of the printing plate thereunder, substantially as and for the purpose 70 specified.

24. In a duplicating machine, a type bed, a frame element extending along the type bed, a ribbon extending crosswise of the type bed, a guide carried by the frame element 75 for guiding a printing plate under the ribbon, and means carried by the guide for raising the ribbon during the insertion of the printing plate thereunder, substantially as and for the purpose set forth.

80 25. In a duplicating machine, a type bed, a frame element extending along the type bed, a ribbon extending crosswise of the type bed, a guide carried by the frame element 85 for guiding a printing plate under the ribbon, and means carried by the guide for raising the ribbon during the insertion of the printing plate thereunder, said means comprising a lever pivoted between its ends to the guide, one arm thereof extending under the ribbon and the other arm being provided with finger-engaging means, substantially as and for the purpose described.

90 26. In a printing machine, a frame, a type bed, a receptacle arranged below the type bed and having a drawer, means for effecting the printing on the paper on the type bed, means for removing the paper from the type bed, and means for directing the paper to the drawer comprising a guide carried by 95 the frame and curved downwardly toward the front of the machine and a deflector at the front of the machine supported by the receptacle and curving over an end of said guide, substantially as and for the purpose 100 set forth.

105 27. In a printing machine, a type bed, a receptacle arranged below the type bed and having a drawer, means for effecting the 110 printing on the paper on the type bed, means for removing the paper from the type bed, and means for directing the paper to the drawer comprising a guide carried by the frame and curving downwardly toward the front of the machine, a deflector at the front 115 of the machine supported by the receptacle and curving over an end of said guide, and a deflector located at the rear end of the drawer, substantially as and for the purpose 120 described.

125 28. In a duplicating machine, a base, a type bed mounted on the base, a frame mounted on the base and movable relatively thereto to expose the type bed, an impression member for coacting with the type bed and ribbon mechanism supported by the frame on opposite sides of the type bed and including guide rollers supported by the frame on opposite sides of the bed and arranged to guide the ribbon over the type

- bed, substantially as and for the purpose set forth.
29. In a duplicating machine, a base, a type bed mounted on the base, a frame mounted on the base and movable relatively thereto to expose the type bed, the frame including frame elements disposed on opposite sides of the type bed and having horizontal flanges on the sides thereof nearest the type bed, an impression roller movable along the upper surface of said flanges, ribbon reels mounted contiguous to the frame elements, and a guide roller mounted on the inner side of each frame element under and near the flange thereof for guiding the ribbon in the horizontal plane across the printing face of the type mounted on the type bed, substantially as and for the purpose described.
30. In a duplicating machine, a type bed, a frame comprising parallel frame elements located on opposite sides of the type bed and in juxtaposition thereto, ribbon reels located on the outside of the frame elements, and guide rollers for the ribbon including detachable members located on the inner sides of the frame elements, a fixed bearing for one end of each of said members secured to the adjacent frame elements, and a companion yielding bearing being secured to the frame between said frame elements.
31. In a duplicating machine, a stationary type bed, a frame, a ribbon extending across the type bed, a printing plate guide supported by the frame and having a portion extending under one side margin of the ribbon, and means for preventing fouling of the plate on the ribbon, substantially as and for the purpose set forth.
32. In a duplicating machine, a stationary type bed, a frame to the outside of the type bed, and a printing plate guide bridging the space between the frame and type bed, a ribbon extending across the type bed, said guide having one end accessible at one side of the machine, and its opposite end projecting beneath one side margin of the ribbon.
33. In a duplicating machine, a stationary type bed, a ribbon movable across the type bed, a frame to the outside of the type bed, and a printing plate guide bridging the space between the frame and type bed, said guide having one end accessible at one side of the machine, and its opposite end projecting beneath the ribbon, and a slidible connection between the guide and frame.
34. In a duplicating machine, a stationary type bed, a frame having parts located on the outside of the type bed, a ribbon extending crosswise of the type bed, a printing plate guide bridging the space between the frame and type bed, and having an end projecting beneath the ribbon, and means associated with the guide for raising an edge of the ribbon.
35. In a duplicating machine, a stationary type bed, a ribbon movable across the type bed, a frame having parts located on the outside of the type bed, a printing plate guide bridging the space between the frame and type bed, and having an end projecting beneath the ribbon, and means associated with the guide for raising an edge of the ribbon, said means including a finger operating member.
36. In a duplicating machine, a stationary type bed, a frame having parts located on the outside of the type bed, a ribbon extending crosswise of the type bed, a printing plate guide bridging the space between the frame and the type bed, and having an end projecting beneath the ribbon, and means associated with the guide for raising an edge of the ribbon, said means including a pivoted frame mounted on the guide.

In testimony whereof, I have hereunto signed my name in the presence of two attesting witnesses, at Syracuse, in the county of Onondaga, in the State of New York, this 23rd day of July, 1909.

JOHN B. WEST.

Witnesses:

S. DAVIS,
E. K. SEEMILLER.
